UNITED STATES PATENT OFFICE.

JULIUS BRENZINGER, OF FAIRFIELD, CONNECTICUT, ASSIGNOR TO SANITARY CAN MACHINERY COMPANY, OF ELLSWORTH, MAINE, A CORPORATION OF MAINE.

FLANGE-CURLING MACHINE FOR CAN-COVERS.

1,287,207.

Specification of Letters Patent. Patented Dec. 10, 1918.

Application filed June 8, 1917. Serial No. 173,491.

To all whom it may concern:

Be it known that I, JULIUS BRENZINGER, a citizen of the United States, residing at Fairfield, in the county of Fairfield and State of Connecticut, have invented certain new and useful Improvements in Flange-Curling Machines for Can-Covers, of which the following is a specification.

This invention relates generally to metal bending machines, with more particular reference to machines for turning or bending portions only of the edge of the flange with which a can top or cover of a certain type is provided, having still more particularly in mind the tops or covers for what are known as "square" cans.

Can heading machines are now more generally provided or equipped with appurtenances for automatically positioning a cover on a filled can in transit and delivering the assembled parts to the seaming mechanism. These so-called assembling and feeding devices or appurtenances usually necessitate the stacking of the covers, the bottom or lowermost cover of the stack being withdrawn for delivery to and positioning on each can-body as the latter passes to the seaming mechanism. Covers having flat—or substantially flat—flanges will nest so closely when stacked that it would be practically impossible to repeatedly pass a separating or feeding tool between the bottom cover and the one next above the same in the assembling operation. In connection with the so-called "round" cans, it was found that the entire edge of the flange might be satisfactorily so bent or turned down in the die-stamping operation by which the cover was formed as to not only have the effect of slightly spacing apart the covers when stacked, and thus make possible the withdrawal of the bottom cover, but also facilitate and improve the action of the seaming rollers.

In connection with so-called "square" cans, however, in spite of the fact that the corners of these cans are rounded, it will be apparent that the action of the stamping dies on the metal along the "straight" edges of the cover differs materially from their action on the metal at the rounded corners. In one case the operation is merely that of bending,

while in the other account must be taken of the necessary flow of metal due to the reduction of surface area. It was found, therefore, that when the entire edge of the flange of a "square" can cover was turned down in the die-stamping operation, apart from the fact that the dies were necessarily expensive both in original cost and in cost of maintenance, the turned-down portion of the flange was lacking in uniformity to a degree which made it impossible to depend upon anything like the uniformly successful production of a practically perfect seam by the seaming mechanism. On this account, packers have been inclined to insist upon the provision of flat-flange "square" can covers, but here, again, arises the difficulty heretofore referred to, of providing automatic assembling and feeding devices for can heading machines which will successfully operate when the covers nest in superposed arrangement, as they necessarily must do if the flanges are flat.

I have found that if the substantially straight portions only of the edge of the flange on opposite sides of a "square" can top or cover are bent or turned down—particularly the edges of the longer sides, for these cans and covers are almost invariably "oblong" rather than "square"—the desirable spacing apart of the stacked covers is provided for without to the slightest extent impairing the seaming operation. In a co-pending application, filed of even date herewith, Serial No. 173,490, I show and describe a "square" can top or cover the edge of the flange of which is curled or longitudinally bent or turned throughout the "straight" portions only on opposite sides of the cover to form depending lips which serve to prevent the nesting of the covers when stacked but which do not interfere in any way with practically perfect operation of the seaming rollers of a heading machine. The principal object of the present invention is a provision of a machine for automatically performing this operation of bending or turning portions only of the flange-edge in the production of a can cover substantially like the one shown and described in my co-pending application, aforesaid.

My invention will be more readily under-

stood by reference to the accompanying drawings, forming a part of this specification, in which—

Figure 1 is a top plan view of a machine embodying my invention;

Fig. 2 is a side elevation thereof, partly broken away;

Fig. 3 is a vertical section, taken substantially on the broken line 3—3 of Fig. 1;

10 Figs. 4, 5, 6, and 7 are enlarged detail elevations of the forming and feeding rollers, illustrating the various steps of the forming or bending operation;

15 Fig. 8 is an edge view of the can cover prior to the shaping of portions of the flange thereof in the machine of my invention;

20 Fig. 9 is a similar view of the same after the flange-bending or shaping operation, and

Fig. 10 is a fragmentary plan view of Fig. 9.

Referring now to the drawings in detail, I prefer that the ordinary flat-flanged covers 25 11 be fed into the machine by gravity, and I therefore mount the bending or forming mechanisms together with their actuating means upon an inclined frame 12 which includes the cover-feed chute 13 and discharge chute 14, rendering the degree or 30 angle of inclination variably adjustable by pivoting the frame 12 as a whole upon a stationary shaft 15 mounted in the top of the standard 16 having a heavy supporting base 35 17. This tiltable frame 12 is releasably secured in any one of various selective angles of inclination by means of a curved arm 18 extending from the lower end of the frame and provided with a slot 19 through which 40 passes a stud 20 on said standard threaded at its end for the reception of the clamping nut 21 acting against said arm 18 through the washer 22.

45 Journalized in the opposite side plates 23 and 24 of the frame 12 are the axles of a plurality of pairs of flange-bending or turning rollers. The chutes 13 and 14 are in alinement, and the pairs of rollers therebetween are so relatively positioned as to 50 receive each cover 11 from the chute 13, operate upon the same in a manner about to be described, and discharge it upon the chute 14 for conveyance by gravity to such destination as may be desired. I have concluded that for best and expeditious results 55 three pairs of these rollers should be employed—not including a pair of transversely arranged idler rollers, which will be hereinafter described—but it will be apparent 60 that a greater or less number of pairs might be employed, if desired, without departing from the spirit of my invention. Therefore, for the purposes of this description, I have shown the frame 12 as carrying what 65 may be termed “first operation” rollers 25

and 25' (Fig. 4), “second operation” rollers 26 and 26' (Fig. 5), “finishing” rollers 63 and 64 (these rollers being identical and one thereof being shown in detail in Fig. 6), and discharging or ejecting rollers 28 and 28' (Fig. 7).

It will be apparent that these rollers may be mounted, adjusted and driven in many different and mechanically approved ways. I prefer, however, to provide a plurality of 75 driven shafts journaled at both ends in suitable bearing blocks which are slidable vertically (considering the frame as horizontally disposed) in slots or ways in the side plates 23 and 24, whereby each lower roller may be 80 properly positionally adjusted and the upper rollers of the pair spring-pressed thereagainst. Therefore, the lower roller 25 of the “first operation” pair is keyed or otherwise suitably secured upon a shaft 29 which 85 is journaled at one end in the bearing-block 30 in the slot or way 31 in the plate 23, and at the other end in a counterpart bearing-block in the slot or way 32 in the plate 34. The upper roller 25' of this pair is similarly 90 keyed or otherwise secured upon the shaft 33 which is journaled at one end in the bearing-block 34 in the slot or way 31 and at the other end in the bearing-block 35 in the slot or way 32.

95 Similarly, the lower roller 26 of the “second operation” pair is secured upon the driven shaft 36 which is journaled at both ends in identical bearing-blocks in the slots or ways 37 and 38 in the plates 23 and 24, 100 respectively, while the upper rollers 26' of this pair is secured upon the shaft 40 journaled in the blocks 41 and 42 in the same slots or ways. The discharge or ejecting rollers 28 and 28' are similarly mounted 105 upon the driven shafts 43 and 44, respectively, and these shafts are correspondingly journaled in identical bearing-blocks in the slots or ways 45 and 46 in the plates 23 and 24.

110 The upper ends of the slots or ways 31, 37 and 45 in the plate 23 are closed by the bar 47, suitably bolted to said plate, and the upper ends of the slots or ways 32, 38 and 46 in the plate 24 are closed by the bar 48, 115 suitably bolted to this plate. I may therefore interpose between all of the upper bearing-blocks and these bars 47 and 48 coil-springs 49, 49, whereby the upper rollers of the pairs may be spring-pressed against the 120 lower rollers thereof.

125 All of these rollers may be provided with integral hubs 50, or these parts 50 may be spacing sleeves interposed between the ends of the rollers proper and the bearing-blocks.

130 On one end of the stationary shaft 15 is rotatively mounted the pulley 51, adapted to be driven in the usual manner from any suitable source of power. This pulley may be

provided with a hub 52 upon which is keyed or otherwise suitably secured a gear 53. This gear 53 meshes with gears 54 and 55 on the shafts 29 and 36, respectively, which respectively mesh with gears 56 and 57 on the shafts 33 and 40. The gear 55 also meshes with an idler gear 58 which, in turn, meshes with the gear 59 on the shaft 43, the latter being in mesh with the gear 60 on the shaft 44. These gears being all of the same diameter and pitch, it is obvious that if the operative portions of the rollers are of the same diameter—as is the case—they will rotate at the same velocity and in a manner to operate upon an interposed cover and advance the same to final ejection upon the chute 14.

In Figs. 4, 5 and 7, I have attempted to show in detail the preferred configuration of one end of each of the rollers to which I have referred, and it is to be understood that the ends of each of these rollers are opposite counterparts. All of the pairs of rollers are so formed and end-flanged as to act only against the flanges on opposite sides of the cover 11. As shown in Fig. 4, the ends of the "first operation" rollers 25 and 25' are so formed as to coöperate to slightly turn or start the curling of the edge of the flange on each of two opposite sides of the cover. The cover is then passed between the pair of "second operation" rollers 26 and 26', the ends of which are so formed, as shown in Fig. 5, as to enhance or accentuate the bend, bringing the same to substantially rectangular configuration.

Projecting inwardly from the side plates 23 and 24 of the frame 12, and suitably positioned, are the brackets 61 and 62 carrying the transversely disposed rollers 63 and 64, respectively. These rollers are idlers and are identical in all respects, one thereof being shown in detail in Fig. 6. Each of these rollers 63 and 64 includes a straight portion 65 and a beveled portion 66, forming therebetween an annular and preferably angular groove which receives the bent flange-edge to straighten—or, possibly, slightly in-turn—and true the same. From the rollers 63 and 64 the now finished cover 67 (Fig. 9) with the depending lip 68 on each of the longer sides thereof, is passed to the discharging or ejecting rollers 28 and 28', the ends of which are formed to engage the remaining flat portions of the edge-curved flange of the cover (Fig. 7) and deliver said

cover to the chute 14 whereon it is conveyed by gravity to a suitable receptacle or to other mechanisms, as may be desired.

I prefer to make the horizontally disposed rollers hollow and mount them upon driven shafts in order that they may be readily removed from the frame and rollers of different dimensions substituted therefor. In this manner, and by substituting chutes of different widths, my machine may be easily and readily adapted to turn the flanges of covers for cans of various dimensions.

Many modifications of minor details of my improved flange curling machine for can covers will doubtless readily suggest themselves to those skilled in the art to which it appertains, and I therefore do not desire to limit my invention to the specific construction herein shown and described.

I claim as new and desire to secure by Letters Patent—

1. In a flange-curling machine for so-called square can covers, the combination, with means for directing a continuously flanged cover into the machine, of a series of pairs of driven rollers acting successively upon the flange edge on two opposite sides only of the cover and coöperating to curl or longitudinally bend said flange portions, a pair of driven rollers similarly operative to eject the finished cover, and a pair of idler finishing rollers interposed between said bending rollers and said ejecting rollers.

2. In a flange-curling machine for so-called square can covers, the combination, with means for directing a continuously flanged cover into the machine, of a series of pairs of driven rollers end-flanged to successively operate upon the flange edge on two opposite sides only of the cover and the rollers of each pair coöperating to curl or longitudinally bend said portions of the flange, a pair of driven rollers similarly operable to eject the finished cover, and a pair of rectangularly disposed idler rollers, one on each side of the cover, interposed between said curling or bending rollers and said ejecting rollers.

In testimony of the foregoing, I have hereunto set my hand in the presence of two witnesses.

JULIUS BRENZINGER.
